UNITED STATES PATENT OFFICE.

WILLIAM SPALCKHAVER, OF BROOKLYN, NEW YORK, ASSIGNOR, BY MESNE ASSIGNMENTS, TO R. HOE AND CO., OF NEW YORK, N. Y., A CORPORATION OF NEW YORK.

PRINTING-MACHINE.

1,156,378.

Specification of Letters Patent.

Patented Oct. 12, 1915.

Application filed May 22, 1907. Serial No. 374,992.

To all whom it may concern:

Be it known that I, WILLIAM SPALCKHAVER, a citizen of the United States, residing at Brooklyn, county of Kings, and State of New York, have invented certain new and useful Improvements in Printing-Machines, fully described and represented in the following specification and the accompanying drawings, forming a part of the same.

10 This invention relates to certain improvements in printing machines.

It is frequently desirable to associate with the product of a high speed web printing machine, additional sheets, such, for instance, as a cover sheet or a specially printed sheet. This has been accomplished heretofore by employing a pair of cutting cylinders, one of which operates as a collecting cylinder, the web product of the high speed printing machine, and the sheet or sheets to be associated therewith, being both delivered to the collecting cylinder and being associated thereon. This construction is, however, open to the objection that there 25 is danger that the cutting devices on the cylinders referred to will trim the cover or specially printed sheet during the collection.

It is the object of this invention to produce a mechanism for use in printing machines, in which specially printed sheets may be associated with collected sheets, these sheets being the product of a high speed printing machine, and to do this in such a way as to avoid trimming the specially printed sheets.

With this and other objects in view, the invention consists in certain parts, improvements and combinations such as will be hereinafter described and more particularly pointed out in the claims hereunto appended.

Referring to the drawings, Figure 1 is a diagrammatic view, illustrating the mechanism embodying the invention. Figs. 2 and 3 are enlarged detail views illustrating the operation of certain cams employed.

Referring to the drawings, which illustrate one embodiment of the invention, 1 indicates a shaft on which a forwarding cylinder 2, of usual construction, is mounted. In the particular construction illustrated, this cylinder is provided with two sets of sheet-taping pins 3, 4, indicated in dotted lines. These pins, and the construction for operating them, are so well known in the art that a detailed illustration or de-

scription is unnecessary. This cylinder 2 operates as a folding cylinder, and to that end is provided with folding means as blades 5, 6, indicated in dotted lines in Fig. 1. These blades may be of the ordinary type and operate in the ordinary way, so that a detailed illustration and description of the various mechanism for operating them is unnecessary. Suitable coöperating devices as a pair of folding rollers indicated at 7 will be employed in connection with these blades.

Co-acting with the forwarding cylinder 2 before referred to, is a collecting cylinder 8, this cylinder being mounted on a shaft 9. This cylinder will be provided with sheet-taking devices, such, for instance, as ordinary pins indicated at 10.

The printing mechanism is not shown, but the web coming from the high speed printing mechanism is indicated at W. This web may pass between bending rollers 11 and drawing rollers 12.

Web cutting devices will be employed in machines embodying the invention, and, while the location of these devices may be varied, in the particular construction shown they are mounted on the cylinders 2 and 8. In the particular construction illustrated, the cylinder 8 is provided with a knife, indicated at 13, and the cylinder 2 with cutting woods, indicated at 14.

With the mechanism as so far described, the web W will be forwarded, cut into sheets, and collected on the cylinder 8, and, after the desired number of collections have been made, the sheets will be taken by the pins 3 or 4, as the case may be, and forwarded and folded off by the forwarding cylinder 2.

Machines embodying the invention will be provided with means for forwarding sheets for association with the sheets which have been delivered to the forwarding cylinder 100 after collection by the cylinder 8. This sheet forwarding mechanism may vary in construction. As shown, a pair of forwarding cylinders 15 are employed, these rollers operating to forward the web W', which 105 runs at a lesser surface speed than the surface speed of the web W. From these forwarding cylinders 15, the web is led between a pair of cutting cylinders 16, 17, these cylinders being mounted on shafts 18, 110 19. These cylinders 16, 17 convert the web into sheets, and these sheets are delivered

between a pair of guides 20, 21. The sheets may be fed between the guides 20, 21 by means of a cylinder 22, this cylinder being mounted on a shaft 23, carried in spring bearings 24, and coöperating with the cylinder 17. The cylinder 17 may be provided with sheet-taking pins, indicated at 25, and the guide 20 may be shaped, as shown, so as to act as a stripper to take the sheets from these pins. An ordinary sheet-retaining guide, as 26, may be employed in connection with the cylinder 17.

Inasmuch as the sheets which are formed in the particular construction shown, by the cutting rollers 16, 17, are running at a lesser surface speed than the sheets cut from the web W with which they are to be associated, it is necessary that these sheets be brought up to the speed of the web sheets. While this may be accomplished in various ways, in the particular construction shown two cylinders 27, 28 are employed for this purpose, the cylinder 28 being provided with the usual sheet-taking pins 29. These cylinders are so timed that the pins meet and take the forward end of the sheet which is being advanced between the guides 20, 21, and, as these cylinders are running at the same surface speed as the cylinders 2, 8, they will bring the sheet up to the surface speed of these cylinders.

At the time when the pins 29 take these sheets, they should be released from the action of the forwarding cylinder 22, which, as has been before pointed out, may co-operate with the cylinder 17. In order to effect this, the shaft 19 may be provided with a cam, as 30, this cam coöperating with a disk 31 on the shaft 23 before referred to, of the cylinder 22. The cam 30 is so timed that its high part will strike the disk 31 at the instant when the pins 29 take the sheet which is being passed between the guides 20, 21. The high part of the cam operating on this disk 31 will force the shaft 23 back against its spring bearings, thus releasing the sheet from the nip of the cylinders 17, 22.

An ordinary sheet guide 32 may be employed, and this guide may be so constructed and located as to assist in holding the sheets both on the cylinder 2 and cylinder 28, as shown.

It will be observed that the sheet delivering devices for delivering the sheets from the web having the lesser speed deliver to the cylinder 2 after the cutting devices 13, 14 have operated, that is, beyond the cutting line. There is, therefore, no liability of re-cutting or again trimming these sheets, because they do not pass between the cutting members carried by the cylinders 2 and 8.

While in the particular construction illus-

trated, the sheets referred to as "specially printed sheets" are obtained from a web, it is obvious that the sheets might be obtained and forwarded from any other source by mechanisms well understood in the art.

It will be further understood that in the operation of the mechanism the forwarding of the sheets, which have been referred to as "specially printed sheets," will be so timed that they will meet the sheets delivered from the collecting cylinder to the forwarding cylinder. There is, therefore, no danger of trimming these specially printed sheets after they have been associated with the sheets which have been collected on the collecting cylinder.

Changes and variations may be made in the construction by which this invention is carried into effect. The invention is not, therefore, to be restricted to the specific construction hereinbefore described and illustrated.

What I claim is:—

1. The combination with a collecting cylinder, of a forwarding cylinder provided with folding means co-acting therewith, said cylinders being provided with coöperating cutting devices, means on the forwarding cylinder for taking sheets from the collecting cylinder, web delivering means, means for advancing sheets at a lesser speed than the speed of the web, and means for bringing the sheets up to the speed of, and delivering them to the forwarding cylinder beyond the cutting line for association with and to be folded off with the collecting sheets delivered to said cylinder by the collecting cylinder, substantially as described.

2. The combination with a collecting cylinder, of a forwarding cylinder provided with folding means co-acting therewith, said cylinders being provided with cutting devices, web delivering means, means on the forwarding cylinder for taking sheets from the collecting cylinder, web delivery devices for said cylinders, web cutting devices, means for advancing a web, said means running at a lesser surface speed than the speed of the web delivery devices, means for cutting sheets from this web, and means for bringing the sheets up to the speed of, and delivering them to the forwarding cylinder beyond the cutting line to be associated with and to be folded off with the sheets delivered to it by the collecting cylinder, substantially as described.

In testimony whereof I have hereunto set my hand, in the presence of two subscribing witnesses.

WILLIAM SPALCKHAVER.
